UNITED STATES PATENT OFFICE.

CLARENCE L. JOHNSTON, OF OAKLAND, CALIFORNIA, ASSIGNOR TO PACIFIC BURT COMPANY, LIMITED, OF TORONTO, ONTARIO, CANADA, A CORPORATION OF ONTARIO.

MANIFOLDING SALES-BOOK.

1,309,289.

Specification of Letters Patent.

Patented July 8, 1919.

Application filed March 29, 1916. Serial No. 87,386.

To all whom it may concern:

Be it known that I, CLARENCE L. JOHNSTON, a citizen of the United States, residing at Oakland, in the county of Alameda and 5 State of California, have invented certain new and useful Improvements in Manifolding Sales-Books, of which the following is a full, clear, and exact description, such as will enable others skilled in the art to which 10 is appertains to make and use the same.

This invention relates to manifolding devices, and with respect to its more specific features, to manifolding salesbooks.

One of the objects of the invention is the 15 provision of a simple and inexpensive form of book wherewith quadruplicate copies may be made.

Another object of the invention is the 20 provision of a practical book of the character referred to wherewith the quadruplicate copies may be made with a minimum amount of material.

Other objects will be in part obvious and 25 in part pointed out hereinafter.

The invention accordingly consists in the 30 features of construction, combinations of elements and arrangement of parts which will be exemplified in the construction hereinafter set forth, and the scope of the application of which will be indicated in the following claims.

In the accompanying drawings forming 35 part of this specification and wherein similar reference characters refer to similar parts throughout the several views,—

Figure 1 is a perspective view illustrating one embodiment of the invention;

Fig. 2 is a side view of Fig. 1;

Fig. 3 is a side view illustrating a form 40 slightly different from that shown in Fig. 1; and

Fig. 4 illustrates the invention embodied in still a different form.

It is to be understood that the illustrations 45 are more or less diagrammatic, for clearer disclosure.

Referring now more particularly to the 50 form illustrated in Figs. 1 and 2, the letters A and B indicate two books or pads, each 55 of which comprises a plurality of leaves bound together at one edge, each leaf having a folded portion lying thereon. The main and folded portions of the leaves of pad A are indicated respectively by the numerals 55 1 and 2, and those of pad B by the numerals

3 and 4. These leaves may be composed of thin paper, such as usually employed for manifolding salesbooks and which is of a relatively opaque character as distinguished from transparent, or tissue leaves, records 60 on which latter are more readily read through the leaves. The leaves of the pad A are preferably bound together in book form by providing each of them with a stub 5 and passing staples 6 therethrough and 65 through a backing 7 comprising a sheet of flexible material, such as Manila paper, which, as will hereinafter appear, may form one of the elements of a binder.

The book B may be composed of opaque 70 sheets similar to the book A, but as the characteristics of the invention best display themselves in connection with transparent leaves, it is preferred that the book B shall be composed of tissue leaves bound together 75 at one edge, each of these transparent leaves having the folded transparent portion 4 lying thereon. Like the book A, the leaves of the book B may be provided with stubs 9 bound together by staples 10 and to a relatively stiff backing member 11 which may be composed of pasteboard or other suitable 80 relatively stiff material.

The books A and B are superposed one on 85 the other, with the bound edges parallel and at the same end of the device, so that the leaves of each book extend in the same direction from the stub ends of said leaves when the books are in superposed relation.

The numeral 12 indicates a transfer leaf 90 having a folded portion 13, this leaf being adapted to be disposed between a leaf of one book and a leaf of the other book, and while viewed in some aspects the transfer leaf may be connected to any suitable part of the book 95 which will permit the same assuming operative position for manifolding purposes, it is preferred to bind the transfer leaf with the leaves of one of the books, as for instance with the leaves of the book A, as illustrated 100 in Figs. 1 and 2, the transfer leaf being bound to the book A with the stubs of the leaves of said book and by the same means. The transfer leaf 12 is a double faced carbon sheet, and the extended portion 13 105 thereof may also be a double faced carbon sheet, although the upper face of the extended portion, when the transfer sheet is in operative position, is not necessarily carbonized.

In the form illustrated in Figs. 1 and 2 it is intended to retain one inscribed copy in the device after each recording operation, and to conveniently permit this, and at the same time provide for the free manipulation of the translucent leaves so that they readily assume operative position on the pad A, the bound end of the book B extends beyond the bound edge of the other book, as illustrated. Also this book is provided with a backing 14 of Manila paper which may be conveniently bound with the leaves of the book B. The backings 7 and 11 are connected in such manner as to hinge on each other at the end of the device opposite the stubs, the axis of this hinge being parallel to the bound edges of books A and B. In the form illustrated in Figs. 1 and 2 this is accomplished by stapling these backings together, as at 15. Preferably also these connected books or pads are secured to a stiff foldable cover, the sides of which are indicated at 16 and 17, being connected by the flexible connection or hinge 18. Thus the backings 7 and 11 hinged together constitute a binder to one leaf, 7, of which the book A is connected and to the other leaf 11 of which the book B is connected. Attachments of the books A and B to the cover may be readily effected by providing the backing 11 with a tongue 11' which engages a bail 12' pivoted to an abutment 13' upstanding from the cover side 17.

While certain features of the invention may be adapted for sidewise operated books, the manipulative features of the device are most practically manifested when embodied in an endwise operating book; that is, in a book in which the manipulation of the leaves takes place toward and from the operator instead of crosswise of the operator, this form comporting with the natural tendency in operating a book for the purpose described, whereas the sidewise operated book presents some less desirable manipulative features which are eliminated in the other form.

In operation, the cover side 16 and the book B are thrown back, whereupon the transfer sheet with its underlying opaque leaves will be presented to the operator, the folded portion 13 of the transfer sheet lying immediately above the portion 12 to which it is directly connected. The free end of the folded portion 1 of the opaque sheet directly beneath the transfer sheet is then grasped between the fingers of the right hand and moved toward the operator until it has escaped the free end of the transfer sheet; the folded portion of the transfer sheet is lifted, and the translucent sheet is disposed in folded condition on top of the main portion of the transfer sheet; then the extended portion of the transfer sheet and the original sheet are folded onto the folded translucent

leaf. The device will then be ready for inscription, and it will be seen that in such position the transfer sheet extends between the translucent sheet of pad B and the opaque sheet of pad A. An inscription made upon the folded portion of the opaque sheet will be duplicated in a positive manner upon the underlying folded portion of the translucent sheet; upon the under face of the main portion of the translucent sheet, 75 and upon the main portion of the opaque sheet. After inscription the opaque sheet is torn from its stub along the weakened line 19 provided to facilitate such operation, and said opaque sheet may be torn apart on the 80 weakened line 20 and proper disposition made of the two leaves thus formed. The free end of the folded portion of the translucent sheet is then grasped and torn from the main portion of the translucent sheet 85 along the weakened line 21 and disposed of as desired. Thereafter the pad A is lifted, moving on its hinge at 15 as an axis, whereupon the main portion of the inscribed translucent sheet will drop onto the backing 90 11 or onto the translucent leaves previously disposed on said backing. The book A is then permitted to drop upon the inscribed translucent leaves and will be ready for a subsequent inscription. As a convenience 95 in manipulation the transfer sheet, near its stub portion, is provided with a cut-out or recess 22 disclosing the free end of the underlying folded opaque sheet; and the free end of the folded portion of the transfer 100 sheet may be cut away so as to register with said recess, as at 23.

In the form illustrated in Fig. 3, it is intended to remove all the leaves from the device, so that when the leaves have become 105 exhausted only the stub portions will be left. In this form, as will be seen, the bound edges of the two books are directly bound together into a single stub portion, as it were, with the outer ends of the stubs 110 in alinement. Also, in this form, both books are provided with manila backings 24 and 25, the one at the bottom and the other at the top. Both the opaque and the translucent leaves of this form are preferably 115 provided with weakened lines in order to enable the leaves to be readily torn from their respective stubs. As all the leaves of the books A and B are to be removed in this form, the hinged binder feature of Figs. 120 1 and 2 is omitted.

Should it be desired to make a record upon the upper side of sheet 3, as for example, if the leaves of the second pad be so opaque that it is difficult to read directly 125 through the sheet the writing on the under side of the sheet 3, an additional carbon sheet may be provided in position to make an inscription on the upper side of the sheet 3. In Fig. 4 this modification of the 130

invention is illustrated in connection with a book of the type illustrated in Fig. 3, except that in Fig. 4 the upper book C corresponding to the book B of Fig. 3 is illustrated as composed of opaque sheets in order that the function of the carbon sheet about to be described may be more clearly manifest. In the form of the invention illustrated in Fig. 4, in order that the inscription may be positively made on the main portion of the opaque sheet C, so as to be directly read, a second transfer leaf 26 is employed and disposed between the main portion 27 of the sheet C and its folded portion 28. Preferably this second transfer leaf is a single face carbon leaf and folds into the operative position at an angle to the plane of movement of the other leaves around their bound portions. For this purpose it may be connected to the manila backing of the pad A, at one side thereof, as at 29, from which position it may be conveniently folded into and out of operative position between the folds of the leaves C.

It will be understood that in either form of the device all the records may be removed, and that if it should be desired to remove the main portion of the transparent sheet of the embodiment of Figs. 1 and 2, this sheet would preferably be provided with a weakened line 30, permitting it to readily tear at a predetermined part.

While the leaves of the pads A and B may be employed in blank form, that is, without printed matter thereon, it is to be understood that in their preferred commercial form the leaves are printed, so as to identify the establishment using them, and are provided with blocked-out spaces for the address of the customer, the goods purchased, and the price of such goods, etc. The printed indicia will be arranged cross-wise of the book parallel to the bound edges of the pads, and the several leaves of each book will be numbered consecutively from 1 to 50, etc., as the case may be, each pad consisting of a series of 1 to 50, etc., main leaves, and the folded leaf of each series being similarly numbered.

In view of the above is provided a construction wherewith are accomplished, among others, all of the objects hereinbefore referred to.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and spe-

cific features of the invention herein described and all statements of the scope of the invention, which, as a matter of language, might be said to fall therebetween.

Having described my invention, what I claim as new and desire to secure by Letters Patent is:—

1. In a manifolding device, in combination, a book comprising a plurality of leaves bound together at one edge, each leaf having a folded portion lying thereon, a second book comprising a plurality of leaves bound together at one edge, each leaf having a folded portion lying thereon, said books being superposed one on the other with the bound edges parallel and at the same end of the device, and a transfer leaf having a folded portion and adapted to be disposed between a leaf of one book and a leaf of the other book. 85

2. In a manifolding device, in combination, a book comprising a plurality of leaves bound together at one edge, each leaf having a folded portion lying thereon, a second book comprising a plurality of leaves bound together at one edge, each leaf having a folded portion lying thereon, said books being superposed one on the other with the bound edges parallel and at the same end of the device, and a double faced transfer leaf having a folded portion and adapted to be disposed between a leaf of one book and a leaf of the other book. 90

3. In a manifolding device, in combination, a book comprising a plurality of leaves bound together at one edge, each leaf having a folded portion lying thereon, a second book comprising a plurality of leaves bound together at one edge, each leaf having a folded portion lying thereon, said books being superposed one on the other with the bound edges parallel and at the same end of the device, and a double faced transfer leaf bound with the leaves of one of said books and having a folded portion 105 adapted to be disposed between the folded portion of a leaf of one book and the folded portion of a leaf of the other book. 110

4. In a manifolding device, in combination, a book comprising a plurality of leaves bound together at one edge, each leaf having a folded portion lying thereon, said books being superposed one on the other with the bound edges parallel and at the same end of the device, a transfer leaf having a folded portion and adapted to be disposed between a leaf of one book and a leaf of the other book, and a second transfer leaf adapted to be disposed between the folds of one of said book leaves. 120

5. In a manifolding device, in combination, a book comprising a plurality of leaves 125

4

bound together at one edge, each leaf having a folded portion lying thereon, a second book comprising a plurality of leaves bound together at one edge, each leaf having 5 a folded portion lying thereon, said books being superposed one on the other with the bound edges parallel and at the same end of the device, a double faced transfer leaf bound with the leaves of one of said books, 10 and a single face transfer leaf adapted to fold into operative position at an angle to the line of movement of said other leaves around their bound portions.

6. In a manifolding device, in combination, 15 a plurality of books connected together and superposed, the leaves of said books being each folded on themselves, and a foldable carbon transfer sheet connected to said device and disposed between said 20 books.

7. In a manifolding device, in combination, a plurality of books connected together and superposed, the leaves of said books being each folded on themselves, and 25 a carbon transfer sheet folded on itself and connected to said device and disposed between said books.

8. In a manifolding device, in combination, 30 a book comprising a plurality of leaves bound together at one edge, each leaf having a folded portion lying thereon, and a second book comprising a plurality of leaves bound together at one edge, each leaf

having a folded portion lying thereon, said books being superposed one on the other 35 with the bound edges parallel and at the same end of the device, the bound edges of said books being bound together, and a double faced transfer sheet bound with the leaves of one of said books and having 40 a folded portion adapted to be disposed between the folded portion of a leaf of one book and the folded portion of a leaf of the other book.

9. In a manifolding device, in combination, 45 a book comprising a plurality of leaves bound together at one edge, each leaf having a folded portion lying thereon, a second book comprising a plurality of leaves bound together at one edge, each leaf having 50 a folded portion lying thereon, said books being superposed one on the other with the bound edges parallel and at the same end of the device, a transfer leaf having a folded portion and adapted to be disposed between a leaf of one book and a leaf of the other book, and a second transfer leaf adapted to be disposed between the folds of one of said book leaves, the leaves 55 of said books being of opaque material. 60

In testimony whereof I affix my signature in the presence of two witnesses.

CLARENCE L. JOHNSTON.
